US0D1073532S

(12) **United States Design Patent** (10) **Patent No.:** **US D1,073,532 S**
(45) **Date of Patent:** **** May 6, 2025**

(54) **AERIAL VEHICLE**

(71) Applicant: **Amazon Technologies, Inc.**, Seattle, WA (US)

(72) Inventors: **Ricky Dean Welsh**, Seattle, WA (US); **Louis Leroi LeGrand, III**, Seattle, WA (US); **Dominic Timothy Shiosaki**, Seattle, WA (US); **Gur Kimchi**, Seattle, WA (US); **Shmuel Eisenmann**, Seattle, WA (US); **Isaac Aaron Margulies**, Seattle, WA (US); **Chris Maynor**, Seattle, WA (US); **Jon T. Braam**, Seattle, WA (US)

(73) Assignee: **Amazon Technologies, Inc.**, Seattle, WA (US)

(**) Term: **15 Years**

(21) Appl. No.: **29/776,691**

(22) Filed: **Mar. 31, 2021**

Related U.S. Application Data

(62) Division of application No. 29/650,291, filed on Jun. 5, 2018, now Pat. No. Des. 917,340.

(74) *Attorney, Agent, or Firm* — Athorus, PLLC

(57) **CLAIM**

The ornamental design for an aerial vehicle as shown and described.

DESCRIPTION

FIG. 1 is a perspective view of an aerial vehicle.

FIG. 2 is a front view of the aerial vehicle of FIG. 1.

FIG. 3 is a rear view of the aerial vehicle of FIG. 1.

FIG. 4 is a right side view of the aerial vehicle of FIG. 1.

FIG. 5 is a left side view of the aerial vehicle of FIG. 1.

FIG. 6 is a bottom view of the aerial vehicle of FIG. 1; and,

FIG. 7 is a top view of the aerial vehicle of FIG. 1.

The broken lines in the drawings depict portions of the aerial vehicle that form no part of the claimed design.

1 Claim, 5 Drawing Sheets
